UNITED STATES PATENT OFFICE

HENRY M. JARVIS, OF WINFIELD, KANSAS, ASSIGNOR OF THREE-FOURTHS TO
CLARION GEORGE COX, OF WINFIELD, KANSAS

PUMPING JACK

Original application filed April 11, 1927, Serial No. 182,788. Divided and this application filed May 16, 1929. Serial No. 363,596.

This invention relates to improvements in pumping jacks.

The primary object of the invention is the provision of an improved pumping jack of the type set forth in my co-pending application, Serial No. 182,778, filed April 11, 1927, of which application the present application is a division; the present invention relating to a sprocket chain type of operating unit, the throw of which may be adjusted to vary the pump throw.

Other objects and advantages of this invention will be apparent during the course of the following detailed description.

15 In the accompanying drawing, wherein for the purpose of illustration is shown only a preferred embodiment of the invention,

Figure 1 is a side elevation of the improved pumping jack.

20 Figure 2 is an edge elevation of the improved pumping jack of Figure 1.

Figure 3 is a sectional view taken through details of the improved pumping jack substantially on the line 3—3 of Figure 1.

25 In the drawing, wherein similar reference characters designate corresponding parts throughout the several views, the letter A may generally designate the improved pumping jack. In connection therewith a rack bar or

30 toothed member 25 is provided, which is connected by a suitable clamp 26 in axial alignment with the polish rod 27 of well pumping equipment. As is well understood by those

35 skilled in the art, the polish rod 27 vertically extends thru a suitable stuffing box or packing 28 above a casing head 29. The rack member 25 is preferably straight and vertical, having teeth 30 arranged along one side thereof. At

40 its lower end it may be attached to the clamp 26 in any approved manner, such as set forth in my co-pending application above mentioned, and at its upper end it is provided with a swivel eye or hook 32.

The frame of the improved pumping jack 45 preferably includes the parallel base pieces 55 and 56, bolted as at 57 in rigid relation upon the well platform, to one side of the casing head 29. Legs 60 and 61 are connected at the outer sides on the ends of each of the

50 base pieces 55 and 56; the said legs being pref-

erably of angle iron and detachably bolted into position as at 62 and 63 respectively. On each of the base pieces 55 and 56, the legs 60 and 61 extend upwardly in relative convergence, and at their upper ends they are secured together in any approved manner, as by means of riveting. In the approved construction a pair of vertical standards 64 and 65 are respectively detachably bolted as at 66, at their lower ends, upon the intermediate portions of the base pieces 55 and 56. The vertical standards 64 and 65 are very strong and preferably of plate or bar material, or they may be of channel formation, if desired. The same are connected at the inner sides of the pieces 55 and 56 respectively, and extend upwardly in spaced parallelism, and, at their upper ends, they are suitably secured to the legs 60 and 61 described, and provided with bearing segments 70 and 71. With 70 these segments 70 and 71 there are provided detachable bearing caps 72 and 73 respectively, in a complementary relation, for rotatably receiving the master gear wheel shaft 75. This shaft at its ends projects beyond the outer sides of the bearings, and at its outer ends it is provided with detachable caps 76, held in position in any approved manner, to permit the said shaft 75 to rotate freely against end movement.

75 The legs 61 are preferably rigidly braced by cross pieces 78 to their adjacent standards 64 and 65, as the case may be; it being the purpose to provide these braces 78 mainly to hold the standards 64 and 65 in a stable definite spaced relation, since the frame is adapted to be swung upon the pivot pin 63 after detachment of the bolts 62 and 66 from the base pieces 55 and 56. Such pivoting construction of the frame is necessary under circumstances where the same should be removed from the vicinity of the polish rod when raising or lowering the same for adding or detaching sections, of the polish rod.

80 In the present form of invention, the 95 pumping jack may be referred to as the sprocket chain type of operating unit. The shaft 75 is provided adjacent the standard 65 with a gear 160, preferably of segmental formation, having a hub 161 and spokes 162 100

radiating therefrom for the support of a rim 163. This rim 163 has teeth 164 thereon meshing with the teeth 30 of the rack 25. The shaft 75 also supports a small sprocket wheel 170, the spokes of which are clamped with the spokes 162 of the gear 160 by means of U-bolts 171, to key the same together. For this form of invention a shaft 90 is used, having the ends thereof bearing in adjustable plates 100 and 101, which are bolted as at 106 onto the standards 64 and 65, in any of the side series of openings 107 which are provided therewith. Rotatable on the shaft 90 is a sprocket wheel 180, larger than the sprocket wheel 170, and keyed with the said sprocket wheel 170 for rotation, by means of an endless sprocket chain 181. A preferably under pull cable 183 is connected at 184 with the sprocket wheel 180, preferably adjacent the rim thereof, for the purpose of oscillating the sprocket wheel 180. If desired, different sprocket wheels 180 may be provided, having different diametrical pitches, and which may be adjusted vertically between and upon the standards 64 and 65, using the same sprocket chain 181. This feature may be used to vary the throw of the pump rod, as will be apparent from the foregoing. It is readily obvious that a rectilinear motion of the polish rod is attained by simple and compact apparatus which may, with facility, be removed for operations made to the polish rod, such as adding of sections thereto, etc. A bracket 110 is attached to the frame legs 60 for guiding the sliding action of rack 25.

Various changes in the shape, size, and arrangement of parts may be made to the form of invention herein shown and described, without departing from the spirit of the invention or the scope of the claims.

I claim:

1. In a pump jack the combination of a supporting frame, a polish rod connecting rack bar having teeth, a gear rotatable on the frame having teeth meshing with said bar, a sprocket wheel keyed with said gear for movement therewith, a second sprocket wheel on said frame, a chain trained about said sprocket wheels, a pull line eccentrically connected on the second sprocket wheel, said second sprocket wheel having a shaft mounting the same on the frame with adjustable means for varying the distance at which it may be placed with respect to the axis of rotation of the first mentioned sprocket wheel.

2. In a pump jack the combination of a supporting frame, a polish rod connecting rack bar having teeth, a gear rotatable on the frame having teeth meshing with said bar, a sprocket wheel keyed with said gear for movement therewith, a second sprocket wheel, a shaft for the second sprocket wheel, adjustable bearings for said shaft, means for connecting said bearings in an adjustable

relation for variation of the distance thereof with respect to the first mentioned sprocket wheel, whereby different sized second sprocket wheels may be used, a chain trained about said sprocket wheels, and a pull line connected on the second sprocket wheel. 70

3. In a pump jack the combination of a supporting frame, a polish rod connecting rack bar having teeth, a segmental gear oscillatively mounted on the frame having teeth meshing with said bar, a sprocket wheel keyed with said segmental gear for movement therewith, a second sprocket wheel rotatable on the frame axially spaced from the first mentioned sprocket wheel and larger in diameter than the first mentioned sprocket wheel, a chain trained about said sprocket wheels, and a pull line eccentrically connected with the second sprocket wheel. 75

4. In a pump jack the combination of a polish rod connecting rack bar having teeth, a supporting frame including vertical spaced standards, a segmental gear rotatable between said standards at the upper ends thereof in mesh with said rack bar, a sprocket wheel keyed with said segmental gear, a second sprocket wheel larger than the first sprocket wheel, means rotatably supporting the second sprocket wheel upon the vertical standards below the first mentioned sprocket wheel and including bearings upon said standards for vertical adjustment of the axis of the second sprocket wheel towards or away from the axis of the first mentioned sprocket wheel, an endless sprocket chain trained over said sprocket wheels, and a pull line eccentrically connected with the second sprocket wheel. 80
